UNITED STATES PATENT OFFICE.

OLIVER CLARK KINGCAID, OF FAIRMONT, WEST VIRGINIA.

WATER-CLOSET.

SPECIFICATION forming part of Letters Patent No. 793,836, dated July 4, 1905.

Application filed January 18, 1905. Serial No. 241,660.

To all whom it may concern:

Be it known that I, OLIVER CLARK KINGCAID, a citizen of the United States, residing at Fairmont, in the county of Marion and 5 State of West Virginia, have invented a new and useful Water-Closet, of which the following is a specification.

This invention relates to water - closets, and more particularly to that class of closets 10 which are provided with trap-valves arranged to be operated automatically by the flushing of the closet-bowl.

Among the objects of the invention are to provide a valve capable of being operated 15 for the passage of water by the raising of the lid, and to so construct said valve as to cause it to be automatically seated by the pressure of water passing through the valve-casing, thus automatically closing the lid.

20 A further object is to so counterbalance the lid that the closure thereof shall be effected by a comparatively slight water - pressure, provision being also made for regulating the counterbalance-weight.

25 With these and other ends in view, which will readily appear as the nature of the invention is better understood, the same consists in the improved construction and novel arrangement and combination of parts, 30 which will be hereinafter fully described, and particularly pointed out in the claims.

In the accompanying drawings, Figure 1 is a vertical transverse sectional view of a closet constructed in accordance with the principles 35 of the invention. Fig. 2 is a sectional view taken on the plane indicated by the line 2 2 in Fig. 1. Fig. 3 is an enlarged sectional view of the valve. Fig. 4 is a detail plan view of the counterbalance-weight. Fig. 5 40 is a horizontal sectional detail view taken on the line 5 5 in Fig. 1, one of the valve members having been removed. Fig. 6 is a perspective detail view of the valve-operating member.

45 Corresponding parts in the several figures are indicated by like characters of reference.

The outer casing 1 of the device is preferably constricted intermediate its upper and lower ends, presenting a hopper-shaped upper portion or member 2, the lower end of

which affords a seat for a diaphragm 3, having a depending annular flange 4, with which the soil-pipe 5 is connected. The diaphragm 3 has a central flanged aperture 6, the flange 7 of which affords a seat for the lower end of 55 the bowl 8. The diaphragm 3 is provided adjacent to opposite sides of the central aperture 6 with a pair of slots 9 9, countersunk, as at 9^a, and through which extend the stems 10 10, carrying the valve members 11 11, 60 which when closed coöperate to form an approximately semispherical cup which constitutes a tightly-fitting closure for the opening at the lower end of the bowl. The stems 10 have a rocking or pivotal movement in the 65 slots 9, and they are provided at their upper ends with wings or enlargements 12, constituting counterweights, whereby the closure of the valve composed of the members 11 is effected, said weights or extensions being 70 readily accommodated in the space between the bowl and the outer casing. The valve members 11 are preferably bolted, riveted, or otherwise suitably connected with the stems 10, which latter are thereby retained 75 in the notches 9 without possibility of displacement and without the necessity for pivotal pins.

Suitably supported, as by a cross-brace 12^a, in the space between the bowl and the outer 80 casing, which latter may be provided with a bulging portion, (shown at 13 in Fig. 2,) is a valve-casing 14, having an inlet 15 which communicates with the upper end thereof and an outlet 16 communicating with its lower end. 85 The inlet 15 is connected with the service-pipe 17, and the outlet 16 is connected by a pipe 18 with an annular flushing-pipe 19, supported at the upper end of the bowl and having a plurality of discharge - openings 20 in the 90 under side thereof. Said flushing-pipe may be partially accommodated in a groove or recess in the under side of the seat 21, which is supported upon the upper end of the casing and which is provided with a hinged lid 22. 95

The valve-casing is provided with an interior seat 23 for an upwardly-opening valve 24, having a stem 25, which is suitably guided in the casing. The lower end of the latter has a packing-gland 26, through which ex- 100

- tends an operating-rod 27, the upper end of which supports the lower end of the valve-stem, so that by an upward movement of the rod 27 the valve will be raised from its seat 5 against the pressure of the water entering through the inlet 15. The valve-operating rod 27 is formed by the short arm of an approximately U-shaped casting or member, the long arm of which, 28, is disposed in rear 10 and exterior of the valve-casing, being connected with the latter by means of a pin or bolt 29, extending through a slot 30 in the arm 28 and connected with the valve-casing, thus permitting the U-shaped member, which 15 includes the valve-operating rod, to have a limited reciprocating movement. The upper end of the arm 28 has a lateral extension 31, which is disposed in the path of a hook 32, connected with the rear end of the lid 22.
- 20 The U-shaped member, which includes the rod 27 and the arm 28 and which as a whole is designated R, is provided with a counter-weight, which is in the nature of a ring 33 having disconnected ends which are provided with lugs 34, which are bolted or otherwise secured to the lower end of the member R. The ring-shaped member 33 extends entirely around the bowl, and it is provided with one or more threaded apertures 35 for 25 the reception of fastening members 36, whereby auxiliary weights, as 37, may be connected with the ring 33 for the purpose of augmenting the weight of the latter.
- 30 From the foregoing description, taken in connection with the drawings hereto annexed, the operation and advantages of this invention will be readily understood.
- 35 When the closet is not in use, the lid, being automatically operated, as will be presently 40 described, is necessarily closed, and the valve, composed of the members 11, likewise forms a tight closure between the bowl and the soil-pipe, thus preventing not only the passage of sewer-gas, but also of backwater, which is 45 sometimes an important consideration. The hook 32 is so disposed with relation to the lateral extension or catch of the member R that it shall not engage said catch until the lid is raised to an approximately vertical position, 50 as shown by dotted lines *a a* in Fig. 2. When the lid is swung beyond an approximately vertical line to a position approximately indicated by dotted lines *b b* in Fig. 2, the hook 32 operates against the catch 31 to raise or 55 elevate the member R, together with the counterweight 33, connected with said member, said counterweight being calculated to counterbalance the weight of the lid. When the member R is thus elevated, the rod 27, 60 which forms a part of said member, will push in an upward direction upon the valve-stem 25, raising said valve from the seat and permitting water to pass from the service-pipe 17 through the valve-casing and the pipe 18 65 to the flushing-pipe 19 and thence into the bowl. The valves 11 will immediately open under the pressure of the water for the passage of water and soil. As soon as pressure upon the lid in the direction of the arrow in Fig. 2 is discontinued the said lid will be automatically closed by the action of the water passing through the valve-casing 14 and impinging upon the upper side of the valve 24 and forcing the latter to its seat, thus lowering the member R and causing the catch 31 70 at the upper end of the arm 28 of said member to exert downward pressure upon the hook 32, connected with the lid. It is obvious that only a comparatively light water-pressure will be needed to perform this service automatically, the lid being practically counterbalanced by the weight member 33.
- 75 It will be observed that in this improved closet the water trap or seal is done away with and that there are no parts liable to be rendered inoperative through freezing as long as the surface-pipe is open. Springs, whether of rubber or metal, are entirely avoided in the construction of this device, the parts of which coöperate easily and efficiently to bring 80 about the desired results.
- 85 It is desired to be understood that while in the foregoing a simple and preferred form of embodiment of the invention has been shown no limitation is necessarily made to the precise structural details herein described, but that the right is reserved to any changes, alterations, and modifications which may be resorted to within the scope of the invention and without departing from the spirit or sacrificing the efficiency of the same.
- 90 Having thus described the invention, what is claimed is—
1. In a device of the class described, a casing having a constricted intermediate portion, a diaphragm supported therein, and a soil-pipe and a bowl connected respectively with the under and upper sides of said diaphragm.
  2. In a device of the class described, a casing having a constricted intermediate portion, a diaphragm supported therein and having a central aperture and a depending annular flange, a soil-pipe connected with said flange, and a bowl connected with the central 100 aperture.
  3. A casing, a diaphragm in said casing having an aperture and a depending annular flange, a soil-pipe connected with the latter, and a bowl connected with the aperture.
  4. A casing, a diaphragm in said casing having an aperture and a flange surrounding said aperture and constituting a seat, a bowl mounted in said seat, stems extending through slots at opposite sides of the aperture, valve members at the lower ends of said stems coöperating to form a closure for the bowl, and counterweights at the upper ends of the stems.
  5. In a device of the class described, a 110

bowl-supporting diaphragm having an aperture communicating with the bowl and provided with slots at opposite sides of said aperture, stems seated loosely in said slots provided with weights at their upper ends, and valve members secured to the lower ends of said stems.

6. In a device of the class described, a casing, a bowl, a bowl-supporting diaphragm in the casing, a weight-operated valve constituting a closure for the bowl, a seat supported upon the casing, an annular flushing-pipe, a lid hinged upon the seat, a water-supply pipe connected with the flushing-pipe, a valve regulating the water-supply, means connected with the lid to open the valve, and counterbalance means connected with the latter.

7. In a device of the class described, a bowl, a flushing-pipe, a valve-casing, a service-pipe connected with an inlet at the upper end of said casing, a pipe connecting the lower end of said casing with the flushing-pipe, a valve within the casing adapted to open upwardly against the pressure of water entering the casing, a lid for the bowl, and means connected with and operable by the lid for raising the valve from its seat when the lid is opened.

8. In a device of the class described, a bowl, a flushing-pipe, a valve-casing, a service-pipe connected with an inlet at the upper end of the valve-casing, a pipe connecting the lower end of said casing with the flushing-pipe, a valve within the casing opening upwardly against the pressure of water entering the casing, a lid for the bowl, and means operable by the lid when the latter has been opened to a position approximating the vertical, for raising the valve from its seat.

9. In a device of the class described, a valve-casing having an inlet near its upper end and an outlet near its lower end, an upwardly-opening valve within the casing having its upper surface exposed to the surface of entering water, a suitably-guided stem for said valve, a packing-gland at the lower end of the casing, and a suitably-guided approximately U-shaped member having an arm extending through the packing-gland at the lower end of the casing and supporting the valve-stem and another arm guided exteriorly upon the valve-casing.

10. In a device of the class described, a valve-casing having an inlet near its upper end and an outlet near its lower end, an upwardly-opening valve within the casing and

exposed to fluid under pressure, a suitably-guided stem for said valve, and valve-operating means including an approximately U-shaped member having one arm guided for vertical movement upon the exterior of the valve-casing and having another arm extended into the casing and supporting the valve-stem.

11. In a device of the class described, a bowl, a flushing-pipe, a hinged lid having a hook-shaped member, a valve-casing, a service-pipe connected with an inlet near the upper end of the valve-casing, a pipe connecting the flushing-pipe with an outlet near the lower end of the valve-casing, a downwardly-closing valve in said casing, and supporting and operating means for said valve including a vertically-reciprocating rod extending into the valve-casing and supporting the valve, an extension of said rod guided exteriorly of the valve-casing and terminating in a catch disposed in the path of the hook member of the lid, and lid-balancing means connected with the valve supporting and operating means.

12. In a device of the class described, a bowl, a flushing-pipe, a hinged lid having a hook-shaped member, a valve-casing connected with the flushing-pipe and with the water-service, a vertically-movable downwardly-closing valve in said casing, a valve supporting and operating member having a rod extending into the valve-casing and supporting the valve, and an arm supported for limited vertical movement exterior of the casing, said arm having a catch disposed in the path of the hook member of the lid, and a weight member consisting of a ring having disconnected ends terminating in lugs connected with the lower end of the valve supporting and operating means.

13. In a device of the class described, a bowl, a flushing-pipe, a hinged lid, a valve controlling the passage of water to the flushing-pipe, valve supporting and operating means operable by the lid, and a lid-counterbalance consisting of a weighted annulus connected with the valve supporting and operating member.

In testimony that I claim the foregoing as my own I have hereto affixed my signature in the presence of two witnesses.

OLIVER CLARK KINGCAID.
